CLIFFORD ROBERTS, OF WINCHESTER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

HEEL LIFT FOR BOOTS OR SHOES

Application filed April 27, 1927. Serial No. 186,876.

The present invention relates to heel lifts for boots or shoes, and more particularly to a heel lift of rubber compound, or similar or equivalent material, adapted for attachment to the lower portion of a shoe heel base and serving as the tread portion thereof.

This application is a continuation in part of the application of Clifford Roberts, Serial No. 36,614, filed June 12, 1925.

Heels of this character, generally known as half heels or toplifts, have long been used to replace the usual heel lifts and provide a cushion for the heel of the wearer. These heels are commonly provided with nail-retaining washers embedded in the rubber body and designed to secure the heel upon the adjacent base. In order to provide a tight, close joint between the rubber toplift and the adjoining heel base, heels of this type were first provided with a sealing rand about the margin intended to secure a close joint through compression of the marginal portion of the heel upon application to the base. Subsequently the heels were made with a pronounced concavo-convex form, or as the section of a hollow sphere, so that the distortion of the heel, in application, from the natural curved form to a flat form would maintain a tight edge by virtue of the natural resiliency of the heel. In the first form of heel, the nail-retaining washers are spaced in close proximity to the margin in order to secure the desired tight edge, and in the second form of heel the washers are grouped within the central area where the lateral spreading upon the application of the heel is least pronounced. In both types of heels the fastening nails must be driven at the points circumscribed by the washers. Due to the difficulty of properly locating and inserting the attaching nails with the heel-attaching machinery used in shoe factories, the concavo-convex form of heel has been practically limited in its use to application by cobblers or shoe repairers.

It has long been recognized that a half heel or toplift, which could be applied to the shoe heel base to provide a tight edge and a secure attachment without an accurate and precise location of the attaching nails, would result in many desirable advantages from the

standpoint of the cobbler or shoe manufacturer. With this end in view, attempts have been made to design such a heel with a core of nail-penetrable material. So far as I am informed, however, these prior attempts were unsuccessful for a variety of reasons; either the core could not be successfully bonded within the body of rubber compound or did not offer a satisfactory medium for holding the attaching nails. In addition, certain of these prior suggestions could not have been successfully employed in connection with half heels or tread lifts, due to the premature exposure of the core and resultant blistering and loosening of the heel after a short period of wear.

I have determined that a very satisfactory type of half heel provided with an embedded core may be produced by the employment of a core having a substantially flat upper or attaching face and an under face shaped in a manner to provide a gradual increase in thickness of the core from the edge portion toward the central portion. This type of core is of sufficient thickness to resist distortion strains incident to the vulcanizing operation, and may be permanently bonded within the surrounding body of rubber in a manner to provide an ideal nailing medium for the rubber half heel without interference with the normal and usual function of the heel during wear. The under surface of the core is preferably shaped in such a manner that the core in section corresponds generally to the average residuum of that portion of the half heel subjected to the greatest wear, or in other words, the under surface of the core, which is generally convex from the central portion toward the thin marginal portions at the sides and rear, is, generally speaking, equidistant from all points of the worn tread surface throughout the area of greatest wear. This results in a completed toplift or heel which may be worn entirely down to the embedded core without prematurely exposing localized portions of the core. In the simplest and most practical form of the invention which I have yet devised, the core at its under surface is provided with a tapered marginal portion extending about the sides and rear

and having an angle of bevel with the plane of the core as a whole which may preferably be less than 35° . The tread face of the finished heel is preferably provided with some 5 form of embossing which determines a nailing area generally coincident with this tapered marginal portion. This embossing may take the form of individual nailing areas or a D-shaped grid. When such a core is em- 10 bedded in the upper portion of a heel body of rubber compound, it has several distinct and important advantages. The core is prefera- bly constructed of a plurality of thin plies of wood with the grain crossed to make a rigid 15 and non-deformable core, which at the same time is readily penetrable by attaching nails. This core is so located in the heel body that the upper flat face of the core abuts the ad- joining face of the heel, and forms in con- 20 junction therewith a rigid and inextensible base for the yielding body of the heel tread. In the present form of the invention the heel body is provided with a sealing rand sloping upwardly from the marginal portion of 25 the core to the outer edge of the heel. This sealing rand projects inwardly over the upper flat face of the core in a manner to provide a locking fin and augment the bonding of the core within the surrounding body of flexible 30 material. In attaching a heel or tread mem- ber of this character, the sealing flange is flattened and distorted substantially into the plane of the upper face of the core, the com- pression of the heel body at the marginal por- 35 tion resulting in a tight, close joint with the heel base. It will be evident to those skilled in the art that in the usual practice of molding, the core is placed upon the bottom of the mold in an inverted position, a rubber biscuit super- 40 imposed thereover, and the whole subjected to vulcanizing heat and pressure. In order to form the locking fin about the margin of the core, the latter is supported throughout its major central area only, leaving the marginal 45 edge about the sides and rear free and unsup- ported. If the pressure upon the inverted core is confined substantially to that portion of the core supported by the bottom of the mold, there is no tendency prior to or during 50 the vulcanizing operation to unduly strain or distort the core into conformity with the supporting face of the mold. With the pres- ent construction, the shape of the core is such that the pressure to which the core is sub- 55 jected gradually decreases as the free mar- ginal edge of the core is approached. This desirable result is accomplished by causing the upper portion of the inverted core to recede from the opposite portion of the mold face 60 as the outer edge of the core is approached, thus providing a space between the upper face of the inverted core and the upper face of the mold which gradually increases in depth or thickness toward the marginal portion of the 65 core. It has been found in actual practice.

that with this construction a core sufficiently thin to adapt it for embodiment in a half heel has the requisite strength and rigidity to undergo the vulcanizing operation without dis- 70 tortion.

The provision of a gradual and relatively wide tapered portion upon the under face of the core permits the desired advantages to be secured without interfering with the attachment of the heel by a possible diversion of the attaching nails, which is not unusual when employing embedded washers or similar ex- 75 peditives.

Referring to the accompanying drawings, Fig. 1 represents a top plan view of a heel 80 embodying the features of the invention;

Fig. 2 is a sectional elevation upon the line 2—2 of Fig. 1;

Fig. 3 is a section upon the line 3—3 of Fig. 1; and

Fig. 4 is a bottom plan view of the heel.

The heel, as shown in the illustrated em- 90 bodiment of the invention, comprises a nail- holding core 10 consisting of three plies, indi- cated respectively at 11, 12 and 13. This core

is provided with a generally heel-shaped con- 95 tour and occupies the major portion of the area within the heel body. Surrounding the core is a heel body 14 of rubber compound, which is molded about the core in the usual vulcanizing operation and which may have any desired character of surface ornamenta- 100 tion or embossing thereon. In the present in- vention, the tread face of the heel body is provided with a series of raised bosses 16, each intended to circumscribe a nailing area.

The attaching portion of the heel body is pro- 105 vided with a sealing rand or flange 18 which is formed by a surface 20 curving upwardly from the junction of the heel body at the mar- 110 gin of the core. As indicated more particu- larly in Figs. 1 to 3, inclusive, the material of the heel body projects inwardly over the core in a manner to form a locking flange 22.

By the attachment of the heel lift to a suit- 115 able base, the sealing rand is flattened out and the core abuts the adjacent surface of the base. This construction insures the retention of a permanently tight edge, due not only to the compression of the marginal portion of the heel body but the permanent locking of the core within the heel body and the insur- 120 ance against loosening of the heel body from the core under the severe pounding incident to the wear of the heel. The under face of the core is substantially convex, tapering from the central portion toward the sides and rear to provide a thin, reduced margin. As indi- 125 cated more particularly in Figs. 2 and 3, the slope of the underface corresponds essentially to the slope of wear of the heel residuum after normal extended use. This is accomplished in the present invention by beveling the under face of the core to provide a gradual taper

corresponding to the slope of wear upon the 130

- heel and insufficient to divert or otherwise interfere with the insertion of the attaching nails. As indicated more particularly, the portion of greatest wear upon the heel is indicated generally by dot and dash lines in Figs. 2 and 3, this wearing area extending over the outer side and rear portions of the heel body and conforming in general to the slope of the tapered edge of the core underlying it. In addition to the advantages hereinbefore enumerated for this type of core, the beveling or tapering of the under face promotes the permanent bond between the core and heel body, due to the fact that the tapered or convex under surface avoids the formation of sharp corners or edges at the sides and rear of the core which are directly subjected to a severe pounding and cutting action in a period of normal wear. With the core not so formed or constructed, this pounding action sooner or later results in a progressive loosening of the heel body and a corresponding shortening of its life.
- What is claimed is:
1. A half heel for boots or shoes comprising a body portion of resilient, vulcanized material capable of being distorted to a substantially flat form in attaching to a heel base, and an embedded and non-deformable core of nail-penetrable material having a flat attaching face adapted to abut directly against the heel base and form the attaching face of the heel and a substantially convex under face terminating in a reduced edge at the sides and rear of the core.
  2. A half heel for boots and shoes comprising a body portion of resilient, vulcanized material capable of being distorted to flat form in attaching to the heel base, a core of nail-penetrable material embedded in the upper portion of the body and having a flat, upper face adapted to abut directly against the heel seat and form the attaching face of the heel, and a comparatively wide and gradually tapered portion extending about the rear and side margin of the core at the under face, and a nailing area upon the tread face of the body substantially coincident with the tapered portion of the core through which attaching nails are intended to be inserted.
  3. A half heel for boots and shoes comprising a body portion of resilient, vulcanized material, a core of nail-holding material embedded in the upper portion of the body and having a flat attaching face adapted to abut directly against the heel seat, and an under beveled portion extending about the sides and rear of the core and a portion of the heel body overlying the core at the margin of the attaching face to assist in locking the core therein.
  4. A half heel for boots and shoes comprising a body portion of resilient, vulcanized material having a depth or thickness approximating one-half the thickness of the shoe
- heel, a flat, non-deformable core of nail-penetrable material embedded in the upper portion of the body and exposed to abut directly against a heel base when attached, and having a lower edge portion elevated above the major portion of the core to increase the effective thickness of the heel body throughout the marginal area.
5. A half heel for boots and shoes comprising a heel body of resilient, vulcanized material having a marginal sealing flange extending about the attaching face, and a non-deformable core of nail-penetrable material embedded in the upper portion of the body and having a flat attaching face which abuts directly against a heel seat during attachment, the marginal portion of the attaching face of the heel body extending over the upper face of the core and adapted to be flattened during attaching to provide a substantially flat attaching face throughout the entire area of the heel.
6. A half heel for boots or shoes comprising a body portion of resilient, vulcanized material, a substantially non-deformable heel-shaped core having a flat attaching face exposed over substantially its entire area with an integral locking fin extending inwardly thereon from the body, and a tapered under margin at the sides and rear not less in width than the locking fin.
7. A half heel for boots or shoes comprising a body portion of resilient, vulcanized material having a generally cupped attaching face, a heel-shaped core embedded therein and having a flat exposed upper face forming the central part of the attaching face, and an under face receding toward the side and rear edges from the opposing portions of the tread surface of the heel.
8. A core for rubber half heels consisting of nail-holding material substantially non-deformable under the strains of the vulcanizing operation, and having a flat upper portion adapted to form the attaching face of the heel when the core is embedded therein, and an under portion tapering from the central area to a relatively thin edge at the sides and rear of the core.
